BLOWER FOR COOLING ELECTRONIC EQUIPMENT CABINETS OR THE LIKE

Winton C. Strumpell, 6027 Corning Ave.,
Los Angeles, Calif.

Filed Dec. 4, 1961, Ser. No. 67,797

Term of patent 14 years
(Cl. D62—4)

FIG. 1.

FIG. 2.

FIG. 3.

FIG. 5.

FIG. 1 is a top plan view of a blower for cooling electronic equipment cabinets or the like showing my new design;

FIG. 2 is a front elevational view thereof;

FIG. 3 is a bottom plan view thereof;

FIG. 4 is a side elevational view thereof, the opposite side, not shown, being substantially the same in appearance;

FIG. 5 is an end elevational view thereof.

I claim:

The ornamental design for a blower for cooling elec-

tronic equipment cabinets or the like, as shown and described.
